UNITED STATES PATENT OFFICE.

CHARLES HENRY HEROD, OF BRANTFORD, ONTARIO, CANADA, ASSIGNOR TO
BRANTFORD COMPUTING SCALE COMPANY, LIMITED, OF BRANTFORD, ON-
TARIO, CANADA.

MEAT-SLICER.

1,323,054.

Specification of Letters Patent. Patented Nov. 25, 1919.

Application filed June 18, 1918. Serial No. 240,612.

To all whom it may concern:

Be it known that I, CHARLES H. HEROD, of the city of Brantford, in the county of Brant, Province of Ontario, Canada, have 5 invented certain new and useful Improvements in Meat-Slicers, of which the following is a specification.

This invention relates to slicers of the type in which the meat is carried on a slide 10 plate movable transversely of a carriage reciprocable parallel to a rotary knife, and my object is to devise simple and effective means for supporting and feeding the slide plate and generally to design the machine 15 so that the operating parts are as completely covered as possible without affecting accessibility.

I attain my object by means of the constructions hereinafter described and illustrated in the accompanying drawings in which—

Figure 1 is a plan view of my improved meat slicer; partly broken away and partly in section;

25 Fig. 2 is a rear elevation, partly broken away and partly in section;

Fig. 3 an end elevation showing the base and carriage only;

30 Fig. 4 a plan view of part of the machine partly broken away to expose the slide plate operating mechanism.

In the drawings like numerals of reference indicate corresponding parts in the different figures.

35 1 is the base, which may be of any suitable form, preferably provided with a continuous top 2 imperforate except as may be necessary for the passage of the operating shaft 3. The means for operating this shaft and 40 for rotating the rotary knife 4 are old in the art and are not herein described nor shown in the drawings.

The shaft 3 actuates the carriage 5 by means of the connecting rod 6. The carriage 45 is provided with rollers 7 which run on the parallel tracks 8 formed on top of the base 1. At one edge of the base parallel to the tracks is formed the guide flange 9. The inner side of this flange is engaged by 50 the shoulder 10 formed on the carriage and its outer side by the retaining strip 11 secured to the carriage. The carriage is thus suitably guided and supported entirely above the top of the base 1, which top may 55 be flush surfaced and imperforate as already

referred to so that no scraps of meat will fall through, and so that the surface is readily kept clean.

The carriage carries the slide plate 12, which is guided by the fixed or stationary 60 guide 13 and the laterally movable guide 14, so that the plate is movable in a direction at right angles to the direction of motion of the carriage. The carriage carries a rack 15 parallel with the guides and facing toward the stationary guide. This rack meshes with a pinion 16 journaled on the carriage and meshing with the pinion 17 secured to the upper end of the spindle 18. The lower end of the spindle has the gear 70 wheel 19 secured thereto meshing with the pinion 20 on the spindle 21 journaled on the carriage. This spindle 21 also has secured thereto a ratchet wheel 22, which is engaged by a spring actuated dog 23 pivoted on a 75 gear wheel 24 loose on the spindle 21. This gear wheel 24 meshes with the rack 25 slidably supported on the carriage parallel to the direction of motion of the carriage. This rack has a finger 26 secured thereto adapted to engage the stops 27 and 28 as the carriage is reciprocated. One of these stops is adjustable, but as the means for adjustment are well known in the art, they are not herein described nor shown in the drawings. 80

85 The result of the construction above described is that as the rack strikes the left hand stop as shown in Fig. 4, the gear wheel 24 is rotated backward a given distance and moves the dog 23 back a given 90 number of teeth of the ratchet wheel. When the finger on the rack 25 contacts with the right hand stop 28 (see Fig. 4) the ratchet wheel is rotated and the gearing is actuated to move the rack 15 and thus feed 95 forward the slide plate 12 ready for the cutting of a fresh slice of meat. It will be seen that this feed mechanism is entirely contained centrally of the carriage and actuates the slide plate along the central line 100 thereof.

To enable the rack 15 to be disengaged from the pinion 16 so that the slide plate may be drawn back to its initial position the movable guide is arranged in the manner I will now describe and connected with the slide plate so as to move the latter as desired.

One or more hooks 47 are secured to the movable guide 14 which engage in a groove 110

48 formed in the upper face of the plate 12 parallel to its edge. The plate is thus free to slide longitudinally of the guide, but when the guide is moved laterally, the plate 5 partakes of the movement and the rack and pinion are engaged and disengaged as the case may be.

Lugs 29 depend from the movable guide 14 and through two of these lugs pass the 10 bolts 30 on which are located coil springs 31, which engage washers 32 secured on the bolts and a flange 33 on the carriage through which flange the bolts pass. These spring actuated bolts thus tend to press the movable 15 guide against the edge of the plate and the plate against the stationary guide 13.

To move the movable guide I provide a rod 34 which is secured to one of the lugs 29 and passes through the sides of the carriage. At the left hand side of the machine 20 as viewed in Fig. 1 I pivot the cam lever 35 on lugs 36, which cam lever engages the end of the rod 34 so that by rocking the cam lever the movable guide may be pushed to the right against the pressure of the springs 25 and the rack 15 disengaged, (see Fig. 4).

The slide plate 12 is provided adjacent the knife 4 with a series of meat holding teeth 37. At opposite sides of the plate adjacent 30 the aforesaid edge, posts 38 and 39 are rigidly connected with the plate. The post 38 has a series of notches 40 formed on its inner side, and the post 39 has a rack 41 formed on its outer side, the teeth of the 35 rack being preferably of ratchet type downwardly directed.

42 is a toothed meat holding bar having at one end a rounded tooth 43 adapted to fit into any one of the notches 40 aforesaid. A 40 dog 44 is provided at the other end of the bar and is adapted to engage the teeth of the rack 41. This dog is movable by means of the spring actuated lever 45 pivoted intermediate its ends and pivotally engaging the dog. The end of the bar 42 and the end 45 of the lever 45 are preferably shaped to form a convenient grip for the operator's hand, so that the bar is readily moved and manipulated. The meat holding bar at the 50 inside of the post 39 is provided with a rounded abutment 46 engaging the inner side of the bar. The tooth 43 being also rounded, the bar is readily rocked more or less so that it may accommodate itself to the 55 surface of the meat with which it may be engaged.

It will be noted that the meat holding bar 60 engages the posts 38 and 39 at the inner side of each post. This entirely prevents a trouble which has been experienced with other types of meat holder in which the pressure against the center of the edge of the slide plate 13 causes the plate to spring,

thus moving nearer together the upper ends of the posts, which frequently disengages 65 the connections of the meat holding bar, besides putting the slide plate out of true. With the present arrangement all the parts are rigidly held in normal position.

What I claim as my invention is:—

1. In a meat slicer, the combination of a 70 slide plate; a carriage provided with a stationary guide for one edge of the plate; a laterally movable guide for the other edge of the plate supported on the carriage; a connection between the movable guide and the plate whereby the movement of the former may be imparted to the latter without interfering with the movement of the plate lengthwise of the slide; a pinion journaled 80 on the carriage; a rack on the plate engageable with and disengageable from the pinion by the lateral movement of the plate aforesaid; and means for driving said pinion to actuate the rack and thereby move the plate. 85

2. In a meat slicer, the combination of a 90 slide plate, a carriage provided with a stationary guide for one edge of the plate; a laterally movable guide for the other edge of the plate supported on the carriage; springs tending to press the movable guide 95 toward the fixed guide; a stem connected with the guide; a cam lever pivoted on the carriage and engaging the stem adapted to move the stem to move the plate away from the fixed guide; and a connection between the movable guide and the plate whereby the movement of the former may be imparted to the latter without interfering with the movement of the plate lengthwise of the carriage. 100

3. In a meat slicer, the combination of a base; a carriage laterally reciprocable on the base; a slide plate movable on the carriage at right angles to the direction of travel of the carriage; a rack slidably longitudinally of the carriage; stops on the base with which said rack is engageable to move it endwise; a loose gear wheel journaled on the carriage meshing with the rack; a spring actuated dog carried by said gear; a ratchet wheel journaled concentric with the loose gear and engaged by said pawl; a pinion concentric with and fast to said ratchet wheel; a spindle journaled vertically on the carriage; a gear wheel fast on the 115 spindle meshing with the pinion aforesaid; a pinion fast on the upper end of the spindle and a rack on the carriage adapted to engage said pinion. 110

Signed at Brantford, this 8th day of 120 June, 1918.

CHARLES HENRY HEROD.
